TORPEDO SHIELD FOR SHIPS

John Cyrus Hardy, North Hollywood, Calif.

Application April 17, 1942, Serial No. 439,303

2 Claims. (Cl. 114—240)

My invention relates to the protection of all types of ships against torpedo attack and particularly to a floating shield adapted to be towed alongside of a ship to activate a torpedo firing pin for exploding the charge at a harmless distance from the ship.

I am aware of attempts to protect warships by the use of so-called "blisters" attached to the hull, but these have the disadvantage of adding weight and substantial drag to the ship as well as permitting the torpedo to explode close to the hull.

It is an object of my invention to provide a torpedo shield for ships which may be towed either by the ship it is designed to protect or by a tugboat, which is of relatively light weight and offers a minimum of resistance to towing, which has the requisite buoyancy to float, preferably below the surface, and which is made and assembled in units, sections or plates which are readily replaceable at sea, and which will cause a torpedo to explode and expend itself at a safe distance from the ship.

More specifically I have discovered that torpedoes may be made to expend themselves against a submerged unobservable shield of plastic or plastic impregnated plywood plate carried or towed vertically under the surface of the water by coupled sections of cable or chain flexible at the coupling. Plastic impregnated plywood being relatively thin, light and water resistant, backed by the incompressibility of water, is easily sufficient to activate a torpedo firing pin which strikes a percussion-detonator, and explodes the charge at a completely harmless distance from the ship. By the use of my invention the shield of plastic plates coupled together may be conveniently carried at a distance of 20 to 40 feet from the side of the ship, according to the size of the ship and the corresponding most suitable distance, and thus render a torpedo almost totally ineffective. While I have found plywood most suitable, as well as economical, it is obvious that other materials having the requisite characteristics may be employed.

These and other objects of my invention will become more apparent from the detailed description thereof which follows.

In the drawings:

Figure 1 is a top plan view of a ship equipped with my torpedo shield. 50

Figure 2 is a side horizontal view of the same, with water in section.

Figure 3 is an enlarged side elevation of a plurality of units or sections comprising my shield. 55

Figure 4 is a top plan view of the leading plate and its coupling with the next adjacent plate.

Figure 5 is a vertical sectional view taken on the line 5—5 of Figure 3.

5 I have illustrated any conventional ship 10 provided with forward booms 11 and stern booms 12 of sufficient length to fix the position of shield 13 preferably at about 25 feet from either side of the ship. This distance, however, is variable. The forward or towing booms should be guyed for strength in supporting the tow, in any well known manner. The stern boom may be omitted in favor of simply a guyed line without a boom. The propeller wash of the ship will tend to hold the shield away from the ship the proper distance.

10 The shield 13 comprises one but preferably a plurality of plates 14 which may for example be made of one-half inch plastic impregnated plywood, or any other relatively light, thin water resistant material. Any kind of wood is adequate, but is preferably treated in a manner to prevent it from becoming water soaked and deteriorating in use. Various methods of preparing the wood are well known.

15 In order to maintain the plates in a vertical position in the water necessary to offset their specific gravity tendency to float to a horizontal position, I employ relatively thin metal keels 15 which may be attached to the lower edge of the plates 14 in any suitable manner, as for example shown in Figure 5 where the keels are inserted in central grooves 16 and held fast by bolts or rivets 17.

20 The lower adjacent corners of the keels 15 are coupled by chains 18, having a removable link, snap or hook indicated at 18a. The weight of the keels 15 and the chains 18 in relation to the volume and weight of the plates 14 together with the other attaching parts hereinafter de-

25 scribed is preferably such that the plates are floated in a vertical position slightly under the surface of the water. There are two primary reasons for the latter: The shield is rendered invisible, and added protective depth is afforded

30 without sacrifice of protection at the surface, for torpedoes are commonly designed to charge submerged.

35 The leading shield is coupled to the ship for towing by a guide cable 20 (preferably steel) attached to the lower part of the shield, and a tow line preferably of hemp 21 having surface buoyancy, connected through the forward boom 11 to the ship. The bottom guide cable is designed to maintain the vertical position of the shield when the ship and shield are making a sharp turn.

It should also be noted that the leading shield is preferably beveled as at 22 to streamline the device. It is also provided with a horizontal type of rudder or stabilizer fin 23 having its nose 24 lower than its tail 25 and also being adjustable to vary the angle of attack, as for example by means of slots 26 through which bolts 27 secure the rudder fin upon the plate 14. The rudder fin need ordinarily be adjusted a few degrees off horizontal, and operates much in the manner of a paravane. An actual paravane might be substituted providing an automatic depth regulating rudder.

The upper edges of the plates 14 are coupled together in any suitable manner, as for example by buoyant hemp lines 28, the leading one of which attaches to the tow line 21; and such lines 28 may be secured to the upper edges of the plates by any suitable form of clamps 30, and are preferably provided with snap couples 28a for quick attachment. Or the coupling may be by chain links, as illustrated at the lower corners of the plates.

The spacing between adjacent edges of the plates is such as to allow flexibility both horizontally and vertically to accommodate rising and falling water currents as well as lateral displacement, as for example when the ship is turning. In order to maintain the line of shields at the same approximate normal level it may be desirable to reduce the weight of the keels on the intermediate plates to compensate for any lifting effect upon the forward and rear end plates arising from the towing line connections.

On the trailing edge of each plate I bolt, rivet or otherwise attach at each side a coupling guide plate 31 which may be flared outwardly to a slight degree, and which overlaps the leading edge of the next adjacent plate. These guide plates 31 perform the functions of reducing turbulence and drag at the joints, and effect a substantially solid shield over the most critical area of the plate junctions. These guide plates may, of course, extend the full depth of the shield if desired. The flaring of the guide plates streamlines the movement of the shield as a whole and at the same time permits slight relative horizontal shifting of the shields.

Even relatively light plates of the character described, backed by the incompressibility of the water, are sufficient to activate a torpedo firing pin, and the effect of an explosion is to destroy individual plates or shields, possibly not more than one, two, or three. As has been explained, these are designed to be readily replaceable by a

boom lift. It may be advantageous to turn the ship about, presenting the shield on the other side toward the attacking submarine, while the damaged or destroyed sections are being replaced, an operation calculated to be possible in an hour's time, causing no delay in the ship's progress. The sections may be replaced with the ship under way. In experiments it has been found that plastic plywood at a suggested thickness of one-half to one inch with beveled cleavage and drag points as described, creates a negligible friction and the towing strain is not excessive from either an engineering nor a power viewpoint. The calculated weight of port and starboard shields for a 10,000 ton ship is about two and a half tons, largely sustained by its own buoyancy.

Although I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent structures.

Having described my invention, what I claim as new and desire to secure by Letters Patent is:

1. A protective device for ships comprising a shield adapted to be towed alongside a ship and having buoyancy and sufficient keel weight to cause it to float in a vertical position and presenting a relatively flat thin and rigid wall to actuate the firing pin of a torpedo when struck, said shield comprising a plurality of sections loosely coupled end to end, and guide plates attached to the trailing edge of each section substantially covering the space between sections and loosely overlapping the leading edge of the adjacent section with a slight outward flare.

2. A protective device for ships comprising a shield adapted to be towed alongside a ship and having buoyancy and sufficient keel weight to cause it to float in a vertical position and presenting a relatively flat thin and rigid wall to actuate the firing pin of a torpedo when struck, said shield comprising a plurality of readily replaceable sections loosely coupled end to end, each section comprising a thin plate of plastic impregnated plywood, and a thin metal keel attached thereto and said keel being of substantial depth to increase the effective area of said section.

JOHN CYRUS HARDY.
